UNITED STATES PATENT OFFICE.

THEODORE N. JONES, OF BOULDER, COLORADO, ASSIGNOR, BY MESNE ASSIGNMENTS,
TO JONES AUTO LOCK COMPANY, OF TACOMA, WASHINGTON.

MEANS FOR CONTROLLING THE PASSAGE OF EXPLOSIVE MIXTURE TO THE ENGINE-CYLINDERS.

1,087,495.

Specification of Letters Patent. Patented Feb. 17, 1914.

Application filed October 7, 1912. Serial No. 724,245.

To all whom it may concern:

Be it known that I, THEODORE N. JONES, a citizen of the United States, residing at Boulder, county of Boulder, and State of Colorado, have invented certain new and useful Improvements in Means for Controlling the Passage of Explosive Mixtures to the Engine-Cylinders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in means for controlling the passage of explosive mixture to the cylinders of internal combustion engines, my special object being to make it practicable to cut off the flow of explosive mixture to the cylinders and lock the controlling mechanism in this position to prevent an unauthorized person from operating an automobile equipped with an engine of this character.

The mechanism is so arranged that the passage leading from the carbureter to the engine cylinders may be closed when the owner leaves the machine. The construction is of such character that only the owner or an authorized person who understands the lock construction will be able to manipulate it for the purpose of opening said passage.

In my present improvement I employ a combination lock construction whose tumblers are adapted to be manipulated by means of rotary tubes arranged one within the other and conveniently accessible to the chauffeur, or person in charge of the machine.

Having briefly outlined my improved construction, I will proceed to describe the same in detail, reference being made to the accompanying drawing, in which is illustrated an embodiment thereof.

In this drawing: Figure 1 is a vertical longitudinal section cutting my improved mechanism, which is shown in position to cut off the passage of explosive mixture to the engine cylinders. Fig. 2 is a similar but fragmentary view of the construction so adjusted as to open the passageway for

the explosive mixture. Fig. 3 is an elevation of the outer extremities of the lock-manipulating tubes. Fig. 4 is a transverse section taken on a line 4—5, Fig. 1, looking toward the right. Fig. 5 is a section taken on the same line, looking toward the left. Fig. 6 is a sectional view of two tumblers showing their parts disassociated. Fig. 7 is a section taken through the dash-board of the automobile in front of the driver, the engine being shown in side elevation, equipped with my improved construction, which is shown on a relatively small scale.

The same reference characters indicate the same parts in all the views.

Let the numeral 5 designate an explosive engine and 6 the main pipe leading from the carbureter, and 7, branch pipes leading to the respective cylinders of the engine.

The main pipe 6 is interrupted by a casing 8 which cuts the same intermediate its extremities, and is in communication therewith. As shown in the drawing, this casing is integral with the pipe. Within this casing is located a core 9 which is disposed longitudinally of the casing, and having its axis coincident therewith. One extremity 10 of this core is threaded into a socket 12 formed in the outer extremity 13 of the casing. This core extends forwardly within the casing and is provided with a tongue 14 exteriorly located thereon and extending longitudinally thereof. This tongue occupies the highest position on the core, or is uppermost when the device is in use. Furthermore, the core is so arranged that the tongue 14 is in alignment longitudinally with a mark 15 formed on the dash-board 16 directly in front of the driver of the machine.

The casing has front and rear projections 17 and 18 respectively from the pipe 6, and a tube 19 is fitted into the casing and adapted, when at its forward limit of movement, to cut off communication between the carbureter 20 and the engine. In order that a fluid-tight joint may be formed around the tube 19 when it enters the open rear extremity of the casing, a stuffing-box 21 is employed. The tube 19 fits closely within the casing, but is rotatably mounted, for a purpose hereinafter explained. A second tube 22 is introduced into the tube 19 from the rear and journaled therein at its outer

extremity, as shown at 23, its inner extremity being connected with a tumbler of the lock, as hereinafter explained.

Within the forward extremity of the tube 19 a tumbler 24 is located, said tumbler consisting of a body member 25 and a ring 26, the two parts being connected by a screw 27. The tumbler is connected with the forward extremity of the tube by means of a pin 28 which passes through a slot 29 formed in the forward extremity of the tube. This pin may be arranged in alignment with a mark 30 formed on the forward extremity of the tube, and the pin may also be diametrically arranged with reference to a slot 31 formed in the member 25 of the tumbler, and of such size as to receive the tongue 14 of the core when the tumbler is so arranged that the slot, or groove, is in alignment with the said tongue.

In order to make provision for properly spacing the tumblers and maintaining them in proper longitudinal position within the tube, and at the same time permit them to be rotated within the tube and upon the core, the tongue 14 is recessed to form projections 32 on the forward portion thereof, the said projections being in alignment with the body member 33 of the tongue, which extends rearwardly beyond the tumbler portion of the device when the latter is in the position to cut off the explosive mixture from the engine.

The body of the tumbler is provided with a perforation 34 in which a spiral spring 35 is located, the inner extremity of the spring bearing against a click-ball 36, while its outer extremity bears against a pin 37 located in the outer extremity of the perforation. This click-ball 36 is yieldingly held in engagement with one of the grooves 38 of the core, the said grooves being so constructed as to allow a segment of the ball to enter, whereby each tumbler is temporarily locked in any desired position of rotary adjustment upon the core. Furthermore, every time a tumbler is adjusted rotatably and moved a space equal to that between the grooves 38 of the core, the ball is suddenly forced into a groove which it enters with a click, thus notifying the person in charge of the mechanism that the tumbler has traveled a single rotary step in its movement on the core.

The member 26 of the tumbler 25 consists of a ring which is adjustable rotatably upon the member 25, the latter being provided with a reduced portion 39 forming a shoulder which is engaged by the inner surface 40 of the ring. In connecting the parts 25 and 26 of the tumbler, any desired relation between the slot 31 of the tumbler and a stop 41 located in a circumferential groove 42 of the ring 26 may be maintained. This stop 41 cooperates with a companion stop, or

projection, 43, formed on a ring 44 constituting a member of another tumbler 45, the ring 44 being connected with the body member 46 of this tumbler by means of a screw 47. This is important, since the second tumbler 45 is manipulated to bring its slot 49 into alignment with the tongue 14, as hereinafter explained.

It may be assumed that the two tumbler members 25 and 26 are so arranged that the stop 41 in the groove 42 is located in longitudinal alignment with reference to the slot 31 and on the same side of the core, and that the projection 43 of the tumbler member 44 is diametrically arranged, while the slot 49 of the tumbler member 46 is in alignment with the slot 31 of the tumbler member 25—see Fig. 1, and it is also assumed that the slots 31 and 49 are diametrically opposite from the tongue 14 of the core. The manner of manipulating these tumblers to bring the slots 31 and 49 into alignment with the core will be readily understood. Under these circumstances, the person who would manipulate the lock for the purpose of effecting a longitudinal adjustment of the tube 19 to bring it into position to open the passage to the part 6 to allow the explosive mixture to flow to the engine, must understand the relation of the position of the mark 30 to that of the slot 31, and, as it has already been explained that the pin 28 connecting the tumbler 24 with the tube is in longitudinal alignment with the mark 30 and that the slot 31, when the tumbler is inserted in the tube, is diametrically arranged with reference to the pin 28, it will be understood that the tube 19 must be given a half turn from the position shown in Fig. 1 in order to bring the slot 31 into alignment with the tongue 14, the latter being uppermost on the core and in alignment with the mark 15 on the dash-board. It is also assumed that the tube 19 is in such position that the mark 30 is in alignment with and adjacent to the mark 15. As the core 9 has ten grooves 38, the operator will know that if he turns the tube 19 five steps, or a sufficient distance to produce five clicks, the slot 31 of the tumbler 24 will be in position in alignment with the tongue 14 and in position to slide longitudinally on the tongue, since the slots of all the tumblers are of such size as to allow the tumblers to move longitudinally on the core when properly adjusted. As soon as the tumbler 24 is in this position, the stop 41 carried thereby will be in engagement with the stop 43 carried by the member 44 of the tumbler 45 and by virtue of the relative position of the stop 43 and the slot 49 of the tumbler member 46, it will be necessary to continue the rotation of the tube 19 and the tumbler 24 another half turn, or five clicks, in order to bring the slot 49 into alignment with the tongue 14

on the same side of the structure, and when this is accomplished the slot 31 of the tumbler 24 would necessarily be in its original position, or on the opposite side of the core from the tongue 14. Hence, a half revolution of the tube 19 in the reverse direction will bring the slot 31 into alinement with the slot 49, both slots being in alinement with the tongue 14 and on the uppermost side of the structure. The two tumblers 24 and 19 to move longitudinally with reference to the core, but the two other tumblers, which I will designate by the numerals 50 and 51, must also be manipulated in a manner that will now be described.

The inner extremity of the tube 22 is connected with the tumbler 50 by means of a pin 52, the said pin entering the member 53 of the tumbler, the latter being connected with the member 54 by means of a screw 55, or other suitable connection. This tumbler 50 carries a ball 56, a spring 57, the said spring causing the ball to successively enter the grooves 38 during the rotation of the tumbler upon the core, the outer extremity of the spring 57 engaging a plug 58. This tumbler 50 is adjacent a tumbler 51 composed of two members 60 and 61, connected by a screw 62, the said tumbler 51 carrying a ball 63 actuated by a spring 64 engaging the ball at one extremity and a plug 65 at the opposite extremity. The tumbler 50 carries a stop 66 which extends into a groove 67 formed in the tumbler 51, and the last-named tumbler is provided with a stop 68 also located in the said groove and in the path of the stop 66. We may now assume that the two slots 69 and 70 of the tumblers 50 and 51 are in alinement with each other, and diametrically arranged with reference to the tongue 14 of the core. It will also be assumed that the pin 52 which connects the tumbler 50 with the tube 22 is diametrically located with reference to the slot 69 of the tumbler, the said pin being in alinement with a mark 71 on the rear exposed extremity of the tube 22. A person, in order to manipulate the lock, must be in possession of this information. He will then turn the tube 22 a half revolution, producing five clicks of the ball 56. This will bring the slot 69 into alinement with the tongue 14 of the core, and also with the slots 31 and 49 of the two tumblers 24 and 45. At the same time the stop 66 will be brought into engagement with the stop 68 of the tumbler 51, and as the rotation is continued another half turn, the slot 70 of the tumbler 51 will be brought into alinement with the tongue 14, and on the upper side of the mechanism. Then by turning the tube 22 a half revolution in the reverse direction the slot 69 of the tumbler 50 will be again brought into alinement with the tongue 14 and in the uppermost position. Hence all

of the tumblers will now have their respective slots in alinement with the tongue 14, and the operator, by pulling rearwardly upon the rear extremity of the tube 22, will move both tubes rearwardly and change the cut-off position of the tube 19,—see Fig. 2. The explosive mixture can then flow readily to the engine in the usual way. When, however, it is desired to stop and leave the engine, the tubes will be again returned to the position shown in Fig. 1, and so manipulated as to throw off the combination in which event no one will be able to open the passage through the pipe 6 to allow the explosive mixture to flow to the engine except the person who knows the combination of the lock mechanism.

It is evident that when the combination is thrown off, the two tubes 19 and 22 may be in any desired relative positions. The operator, however, in order to unlock the structure, will first turn the tubes into position to bring their marks 71 and 30 into alinement with the mark 15 of a dash-board. He will then know that he must give each tube a complete rotation in one direction, and a half rotation in the reverse direction, in order to be able to move the tubes longitudinally upon the core whereby the passage through the pipe 6 may be unobstructed. It is evident that any other desired arrangement or combination may be obtained by changing the relative positions of the members of the various tumblers. For instance, instead of connecting the two tumbler members 25 and 26 in such a manner that the stop 41 will be diametrically arranged with reference to the stop 43 of the tumbler 45, the stop 41 may be so arranged that only two clicks will be necessary during the manipulation of the tumbler 24 to bring the stop 41 into engagement with the stop 43. Then it will be necessary to turn the tumbler 24 five clicks in order to bring the slot 49 into alinement with the tongue 14 on the same side of the structure. Then a reverse movement of two clicks only will be necessary to bring the slot 31 into alinement with the tongue 14 on the same side of the structure. In this way, it will be understood that a great variety of combinations may be obtained, and that any combination may be made as complicated as may be desired.

As illustrated in the drawing, the inner tube 22 is provided with a collar 72 adapted to engage a shoulder 73 formed on the outer tube 19, whereby the rearward movement of the pipe 22 will carry the pipe 19 therewith, while the forward movement of the tube 22 will, by its pressure on the tumbler 46, carry the tube 19 forwardly, since the tumbler mechanism is closely interposed between the forward extremity of the tube 22 and an interior collar 74 threaded into the forward extremity of the tube 19, this ring 74 being

introduced after the tumbler mechanism is in place.

It should be understood that one tumbler member of each tumbler is provided with a series of threaded recesses 75, while its companion member is provided with a single recess 76, whereby a screw inserted in the last-named recess may enter any one of the recesses 75 of the companion tumbler member, thus making it practicable to change the relative positions of the stop 41, for instance, of one tumbler member with reference to the slot 31 of its companion member, and whereby the relative position of the stop 41, for instance, of one tumbler member, may be varied with reference to the stop 43, for instance, of an adjacent tumbler.

The outer exposed extremities of the tubes 19 and 22 may be provided with marks 77 corresponding in number with the grooves 38 of the core, and correspondingly numbered,—see Fig. 3. This, however, is not necessary, since the clicks incident to the engagement of the balls with the grooves of the core as the tumblers are manipulated, will enable the operator to know the exact distance traveled by either tube in a rotary direction, since ten clicks indicate a complete revolution. The outer extremities of the two tubes are milled, as shown at 78 and 79, to facilitate their manipulation. It will be understood that the two tubes 19 and 22 are concentrically arranged, whereby their axes are coincident.

In order to limit the upward movement of the tube structure to a position when it has been withdrawn far enough to completely open the passage-way through the conduit 6, the outer tube 19 is equipped with a stop-collar 80 which, when the tubular construction has been withdrawn to the position shown in Fig. 2, will engage a shoulder 81 mounted on the dash-board of the machine. This makes it practicable for the person in charge of the machine to open the tube 6 for the passage of explosive mixture, to its full capacity, without exercising any special care, since he is only required to draw outwardly on the tube structure until the stop-collar 80 engages the said shoulder.

Attention is called to the fact that the pin 28 which connects the tumbler 24 with the operating tube 19, enters the ring member 26 of the tumbler 24, since this ring member may always maintain a predetermined relation with the slot 29 of the said tube. It is important that this pin be connected with the ring member 26 rather than the body member 25 of the tumbler, since in changing the combination the relative position of the member 25 within the tube will vary as the combination is changed, and it is desirable that the pin 28 should remain fixed within the tumbler. Both of the pins

28 and 52, by virtue of the fact that they enter the ring members of the tumblers, may remain fixed within their tumbler members regardless of the relative change which takes place between the body members of the tumblers and the tubes within which they are located. As these pins engage slots which are open at the rear extremities of the tubes when the latter are removed from the casing for the purpose of changing the combination, the tumbler structure may be disengaged from the tubes at their rear extremities when the interior collar 74 is removed from the tube 19. Attention is also called to the fact that the stop-collar 80 is adjustable on the tube 19, since by removing its fastening screw 82, it may be moved toward the rear extremity of the tube 19 as the latter is withdrawn from the casing, thus making it practicable to completely remove both tubes from the machine when, for any reason, it may be desirable, as for the purpose of changing the combination of the lock. It will be understood that when these tubes are removed the core 9 will remain fixed within the casing, and the tumbler construction may be readily withdrawn from the rear extremities of the tubes, and adjusted for the purpose of changing the combination, as will be readily understood.

Having thus described my invention, what I claim is:

1. In a means for controlling the passage of explosive mixture to the engine cylinders, the combination with a conduit in communication with the cylinders, of a tube adapted to intersect the conduit, and rotatably mounted, a lock located within the tube for maintaining the latter in position to close the passage through the conduit, and an operative connection between the tube and the lock whereby the lock may be manipulated by the rotation of the tube, substantially as described.

2. The combination with a conduit having a transverse opening, a tube entering said opening and rotatably mounted, a lock within the tube, and an operative connection between the tube and lock whereby the latter may be manipulated for locking and releasing the tube as the latter is rotated.

3. The combination of a conduit having a transverse opening, and casing members extending in opposite directions from said opening, a tubular cut-off passing through said opening and journaled in the casing members, a lock within the tube, and an operative connection between the tube and lock to manipulate the latter to lock and release the tube, the latter being slidably mounted to permit withdrawal when unlocked, from its cut-off position within the conduit.

4. The combination of a conduit having

- an opening and provided with casing members extending from said opening in opposite directions, a tube extending through the conduit passage and journaled in said 5 casing members, a stationary support extending into the tube, a lock mounted on said support, and an operative connection between the lock and the tube whereby the lock may be manipulated by the rotary action of the tube, to lock and release the tube, the latter being slidable when unlocked to permit movement to open the conduit. 10
5. The combination with a conduit having a transverse opening and a casing in communication with said opening, a tubular cut-off movable in said casing, a stationary support extending into the tubular cut-off, a combination lock mounted on said support, 15 and an operative connection between the cut-off and the lock whereby the latter may be manipulated to lock and release the cut-off. 20
6. The combination with a conduit having a casing in communication therewith and open at one end, a tube located in said casing and adapted to pass through the conduit whereby the passage through the latter is interrupted, a core mounted on the casing 25 and extending into the tube, lock tumblers rotatably mounted on the core, and an operative connection between the tube and tumblers to allow the latter to be manipulated to permit the withdrawal of the tube 30 and lock tumblers, substantially as described. 35
7. The combination with a conduit having a transverse opening and a casing extending on opposite sides of the conduit, one end of the casing being closed and the other 40 end open, a tube located in said casing and being both rotatably and slidably mounted therein, a core mounted on the casing and extending axially into the tube, a tumbler lock mounted on the core, the latter being 45 provided with a tongue and the tumblers having slots of sufficient width that when the slots of all the tumblers are in alinement, the tumblers will slide freely on the core, and an operative connection between 50 the tube and the tumblers and between the tumblers whereby as the tube is rotated the tumblers may be manipulated to lock and release the tube. 55
8. The combination of a conduit having a transverse opening therethrough, a casing comprising two members carried by the conduit and extending in opposite directions from the conduit, the casing having a core centrally arranged therein and provided 60 with a tongue projecting from the core, tumblers rotatably mounted on the core and having slots to permit the tumblers to slide longitudinally on the core when the slots are in proper alinement, a tube journaled in 65 the casing and connected with one of the tumblers for manipulating purposes, and a second tumbler connected in operative relation with the first-named tumbler, whereby as the tube is rotated the tumblers may be adjusted to bring their slots into alinement 70 with the tongue of the core, the tube being longitudinally slidable in the casing and arranged to carry the tumblers with the tube during the outward movement of the latter whereby the conduit is opened, substantially 75 as described. 80
9. The combination of a conduit having a transverse opening, and casing members extending therefrom in opposite directions, one casing member being closed and the other open, a tube inserted in the open casing member and rotatable and slidable therein, the closed casing member being provided with a stationary core having a tongue on one side, a second tube annularly arranged within the first-named tube, tumblers rotatably mounted on the core and having slots of such size that when all of them are in alinement with the tongue of the core, the tumblers may be moved longitudinally on the core, an operative connection between certain of the tumblers and one tube and certain other tumblers and the other tube, whereby as the tubes are rotated, the tumblers may be manipulated 90 to bring their slots into alinement with each other and with the tongue of the core, substantially as described. 95
10. The combination with a conduit provided with a transverse opening and having a casing composed of members extending in opposite directions therefrom, one casing member being closed and the other open, a stationary core mounted on the casing and extending axially thereto, a tube engaging 100 the casing and adapted to be adjusted to cut off the passage of fluid therethrough, a second tube annularly arranged within the first-named tube, the two tubes being mounted to rotate independently of each other, tumblers rotatably mounted on the core, certain of the tumblers being connected in operative relation with the other tube whereby as the tubes are rotated the tumblers are manipulated, the tumblers being located 105 within the outermost tube, and suitable means inserted in one end of the last named tube for retaining the tumblers in place, the outer tube being slidable in the casing, the latter having a stuffing-box applied to the 110 casing member, substantially as described. 115
11. The combination with a conduit having a transverse opening and a casing composed of members extending on opposite sides of said opening, the casing having a 120 centrally arranged core carrying a tongue, a tube journaled within the casing and adapted to be arranged to close the passage therethrough, tumblers rotatably mounted on the core and having slots adapted to be 125 130

brought into alinement with the tongue of the core to permit the tumblers to move on the core, means for retaining the tumblers within the tube, a second tube annularly arranged within the first named tube, certain of the tumblers being connected in operative relation to one of the tubes and certain of the tumblers being connected in operative relation to the other tube, the various tumblers carrying spring-actuated elements, and

the core being provided with a series of longitudinal grooves adapted to be engaged by the said elements during the rotary action of the tumblers, substantially as described.

In testimony whereof I affix my signature 15 in presence of two witnesses.

THEODORE N. JONES.
